ATTORNEY.

UNITED STATES PATENT OFFICE.

JAMES SMITH, OF GLASGOW, SCOTLAND.

LIQUID-FUEL BURNER.

Application filed March 17, 1922. Serial No. 544,539.

To all whom it may concern:

Be it known that I, JAMES SMITH, of 120 Salkeld Street, Glasgow, Scotland, a subject of the King of Great Britain, have invented certain new and useful Improvements in Liquid-Fuel Burners, of which the following is a specification.

This invention relates to that type of liquid fuel burner having a perforated plate, or plates, over the exterior surface of which the liquid fuel is distributed in a film, or layer, where it is subjected to the comminuting energy of jets of air or steam, or both (hereinafter termed the comminuting agent) issuing through the perforations in the plate, or plates.

I have found that the heating capacity of such a burner as previously proposed cannot be easily regulated by means of the usual control cocks, except within very confined limits, without seriously impairing the efficiency of the burner and rendering it economically unsuitable for many purposes. For example, when such a burner is employed for firing a steam generator or boiler, considerable waste of fuel is likely to occur in starting up the burner and when the boiler is running light or without load owing to the difficulty of regulating the proportions of fuel and the comminuting agent to obtain proper combustion simultaneously with the required reduction in the heating capacity.

The principal object of my present invention is to obviate this disadvantage and to the attainment of this end the invention consists in an improved burner of the type stated, wherein the burner is divided to form separate portions each having its own supply of fuel and of the comminuting agent, so that said portions can be made to operate conjointly or separately, as required, and reduction in the heating capacity of the burner can be obtained simply by shutting off one or more portions without having to regulate the supply of fuel and of the comminuting agent to the portion, or portions, remaining in operation.

In carrying the invention into practice the interior of the burner box or casing, is preferably, subdivided into separate chambers by a partition, or partitions, in such manner that the perforated plate, or plates, is, or are, common to said chambers and provision is made for supplying air and (or)

steam to each chamber and fuel to the exterior surface of each portion of the perforated wall, or walls.

Various constructional forms of the improved burner are illustrated, by way of example, on the accompanying drawing, to which reference will now be made and whereon:

Fig. 1 is an end view and Fig. 2 a cross section of one form of the burner having an inclined burner plate.

Figs. 3 and 4 are sectional elevation and plan views of another form of burner having a flat burner plate.

Fig. 5 is an elevation and Fig. 6 a corresponding cross section of another form of the burner having a ridged burner plate.

1 indicates the burner box or casing having a flat, inclined, convex or ridged cover or burned plate 2 over which the liquid fuel is distributed in a thin layer or film, the plate being provided with perforations 3 and, if desired, with nozzles 4, through which jets or streams of air, or steam, or both are forced into the fuel. 5 denotes a ridge formed on the lower or outer edge of the burner plate to prevent liquid fuel overflowing and 6 is a pipe for returning surplus fuel to the source of fuel supply.

The form of burner illustrated by Figs. 1 and 2 is particularly suitable for attachment to the firedoor, or for location in the firedoor opening, of a furnace. It is triangular in cross-section, presenting an inclined burner plate 2, and has a partition 7 dividing it horizontally into two portions or compartments 8, 9, to which the comminuting agent is separately supplied by pipes 10, 10^a. Liquid fuel is supplied to the exterior surface of the perforated burner plate by way of pipes 11, 11^a and 12, 12^a and nozzles 13, 13^a, one set of pipes and nozzles being provided for each portion of the burner and the nozzles being located on the burner plate at a height corresponding to the top of the respective compartment 8 or 9. By the proper manipulation of control cocks 14, 15, and 14^a, 15^a, supplies of liquid fuel and of the comminuting agent can be made to one or both portions of the burner as required. One portion of the burner, say, the lower portion, is used for starting up and running light or without load, and the other por-

tion is used for running the boiler at full load.

tion, say the top portion, is brought into action when the full heating capacity of the burner is required. Once the control cocks have been set to give the correct proportions 5 of fuel and the comminuting agent, further fine adjustment is unnecessary as the heating capacity of the burner can be economically regulated by simply shutting off the cocks or opening them to the initial 10 setting so as to operate with one or both portions of the burner.

Figs. 3 and 4 show a circular form of burner specially adapted for use in cupolas and other furnaces for heating and melting 15 metals. In this form, the partition 7 subdividing the casing 1 is cup-shaped and the pipe 11 supplies fuel to the annular portion 8 by way of an annular recess 16 in the bottom of the burner and thence by a ring of 20 nozzle pipes 13 to the flat burner plate 2. Similarly the pipe 11^a for supplying fuel to the inner portion 9 of the burner communicates with a ring pipe 12^a and an inner ring 25 of nozzles 13^a. Channels 17 (Fig. 4) are shown cut in the burner plate leading from the fuel nozzle outlets 13 and 13^a to the adjacent perforations 3 in the plate. Control cocks 14^a, 15^a, and 14, 15, are provided as before to enable one or both portions of the 30 burner to be used as required.

The oblong form of burner illustrated by Figs. 5 and 6 is particularly suitable for use in the firespace of a marine boiler. In this form the cover or burner plate 2 is ridged 35 longitudinally after the manner of a roof (Fig. 6). The partitions 7, subdividing the casing is channel shaped and two fuel nozzle pipes 12^a, 12^a, are provided for the portion 9.

When air is used as the comminuting agent 40 in the improved burner described, the blast may be obtained by an ordinary blower or fan or a pump, and I may arrange that the air drawn in by the same passes over or through the fuel in the fuel tank and be- 45 comes charged more or less with fuel vapor on its passage to the burner casing. The air and the fuel may be heated in any convenient manner before being passed to the burner.

To assist the even distribution of the 50 liquid fuel over the burner plate, I prefer to cover the exterior surface of the plate with gauze.

Having now fully described my invention 55 what I claim and desire to secure by Letters Patent is:-

1. A liquid fuel burner comprising a casing having a perforated wall, means dividing the casing to form separate compartments to which said wall is common, means for distributing liquid fuel independently over the exterior surface of the perforated wall of each compartment, and means for supplying a suitable comminuting agent to 60 each compartment independently.

2. A liquid fuel burner comprising a casing having a perforated wall, means dividing the casing to form separate compartments to which said wall is common, means for distributing liquid fuel independently 70 over the exterior surface of the perforated wall of each compartment, means for supplying a suitable comminuting agent to each compartment independently, and means for returning surplus fuel from the perforated 75 wall to the fuel supply.

3. A liquid fuel burner comprising a casing having an inclined perforated wall, means for distributing the fuel in a film 80 over the exterior surface of the perforated wall, and means dividing the casing to form separate compartments for the supply of fuel and of the comminuting agent.

4. A liquid fuel burner comprising a casing having a detachable perforated burner 85 plate, a partition dividing the casing into separate compartments, a fuel distributing pipe in each compartment communicating through perforations in the plate with the exterior surface thereof, and means for supplying a suitable comminuting agent to each 90 compartment independently.

5. A liquid fuel burner comprising a casing having a detachable perforated burner plate, a partition dividing the casing into 95 separate compartments, a fuel distributing pipe in each compartment communicating through perforations in the plate with the exterior surface thereof, means for supplying a suitable comminuting agent to each 100 compartment independently, and means for controlling the supply of fuel and of the comminuting agent to each compartment independently.

6. A liquid fuel burner comprising a casing having a perforated wall, nozzles projecting above the exterior surface of the wall, means for distributing liquid fuel over the exterior surface of the perforated wall, and means dividing the casing to form separate 110 compartments for the supply of a suitable comminuting agent.

7. A liquid fuel burner comprising a casing having an inclined perforated wall, nozzles projecting above the exterior surface 115 of the wall, means dividing the casing to form separate compartments to which said wall is common, means for distributing liquid fuel independently over the exterior surface of the perforated wall of each compartment, and means for supplying a suitable 120 comminuting agent to each compartment independently.

8. A liquid fuel burner comprising a casing having a detachable perforated burner 125 plate, nozzles projecting above the exterior surface of the plate, a partition dividing the casing into separate compartments, a fuel distributing pipe in each compartment communicating through perforations in the plate 130

with the exterior surface thereof, and means for supplying a suitable comminuting agent to each compartment independently.

9. A liquid fuel burner comprising a casing having a detachable perforated burner plate, nozzles projecting above the exterior surface of the plate, a partition dividing the casing into separate compartments, a fuel distributing pipe in each compartment communicating through perforations in the plate with the exterior surface thereof, means for

supplying a suitable comminuting agent to each compartment independently, and means for controlling the supply of fuel and of the comminuting agent to each compartment 15 independently.

In testimony whereof I affix my signature in presence of two witnesses.

JAMES SMITH.
